PROCESS FOR THE MANUFACTURE OF A THIOPHAN DERIVATIVE

Otto Schnider, Jean-Pierre Bourquin, and André Grüssner, Basel, Switzerland, assignors to Hoffmann-La Roche Inc., Nutley, N. J., a corporation of New Jersey

No. Drawing. Application January 29, 1946, Serial No. 644,186. In Switzerland February 2, 1945

2 Claims. (Cl. 260—309)

1

The present invention relates to the manufacture of a thiophan derivative.

Patent No. 2,417,326 (application Ser. No. 585,570 of which the instant application is a continuation-in-part) embodies a process for the manufacture of thiophan derivatives related to biotin, of the following general formula:

wherein X is an alkyl radical or an omega-substituted alkyl radical. Thereby, 2-X-3-oxo-thiophan-4-carboxylic-acid-esters are employed as starting materials which are converted in several steps by way of 2-X-thiophan-3,4-dicarboxylic-acid-ester into the previously mentioned compounds. In accordance with the present invention, a compound having the activity of biotin is obtained if 2-(omega-methoxy-butyl)-thiophan-3,4-dicarboxylic-acid-ester is used as starting material. This compound consists of a mixture of stereoisomeres; the preparation and properties of the material, which represents an intermediate product in the process of the said patent, are described in the patent specification cited above.

According to application 585,570, thiophan-one-(3)-carboxylic-acid-esters can be used as starting materials for the manufacture of derivatives carrying in position 2 an alkyl radical or an omega-substituted alkyl radical. Compounds carrying, apart from alkyl radicals, for instance the following radicals, may be employed: omega-hydroxyalkyl-, omega-alkoxyalkyl-, omega-aryloxyalkyl- or omega-halogenalkyl-radicals. The thiophan-one-(3)-carboxylic-acid-esters (I), which carry a suitable substituent in position 2, are initially converted into the corresponding anhydrides (II) by means of hydrocyanic acid. The same are saponified without further purification and the resulting dicarboxylic acids (III) esterified. The 3-hydroxythiophane-3,4-dicarboxylic-acid-esters (IV), substituted in position 2, are oils capable of being distilled. Upon reacting with halides of phosphorus and sulphur, e. g. thionyl chloride, they are transformed into the 3-chlorine-esters (V). By means of reducing agents the halogen can be eliminated, whereby the thiophan-3,4-dicarboxylic-acid-esters (VI), substituted in position 2, are obtained. This synthesis may be illustrated by the following

2

reaction scheme, which appears in our pending application 585,570:

In these formulae, R stands for lower alkyl, and X is an alkyl radical, or an omega-substituted radical, and more particularly, an aliphatic omega-substituted alkyl radical.

A specific method for preparing the dicarboxylic-acid-ester, according to our application 585,570, is given as follows:

80 parts by weight of finely powdered potassium cyanide are added to a solution of 18 parts by weight of 2-methyl-3-oxo-thiophan-4-carboxylic-acid-ethyl-ester in 500 parts by volume of ether. While stirring and cooling well, 90 parts by volume of concentrated hydrochloric acid are added dropwise in the course of about 2 hours. After evaporation of the ether, 300 parts by volume of ethyl alcohol and 300 parts by volume of concentrated hydrochloric acid are added to the remaining 2-methyl-3-hydroxy-3-cyano-thiophan-4-carboxylic-acid-ethyl-ester; saponification is effected by first slowly distilling off the alcohol and then allowing the product to stand in a boiling water bath for another 2 hours. By concentration in vacuo, 2-methyl-3-hydroxy-thiophan-3,4-dicarboxylic-acid is obtained, which can be converted into the 2-methyl-3-hydroxy-thiophan-3,4-dicarboxylic-acid-diethyl-ester without further purification by means of ethyl alcohol and hydrochloric acid. It boils at a pressure of 0.05 mm. at 101 to 102° C. as an almost colourless, viscous oil.

262 parts by weight of 2-methyl-3-hydroxy-thiophan-3,4-dicarboxylic-acid-diethyl-ester are dissolved in 500 parts by volume of chloroform

and successively treated with 80 parts by volume of pyridine and 119 parts by volume of thionyl chloride while cooling well with ice. The product is first allowed to stand for 2 hours and then heated for about 40 minutes in a boiling water bath until the evolution of gas has ceased. Thereupon, the product is poured on ice, divided in a separating funnel and washed with water and dilute sodium carbonate solution until neutral reaction sets in. The 2-methyl-3-chlorothiophan-3,4-dicarboxylic-acid-diethyl-ester separated from the chloroform boils at a pressure of 0.1 mm. at 100 to 102° C.

186 parts by weight of sodium-iodide hydrate are added to a solution of 280 parts by weight of 2-methyl-3-chloro-thiophan-3,4-dicarboxylic-acid-diethyl-ester in 4000 parts by volume of 80 per cent. acetic acid, and 1400 parts by weight of zinc dust introduced in small portions in the course of about 4 hours while stirring. Each time slight warming set in. After further stirring for about 12 hours, the zinc acetate is separated, the acetic acid removed by distillation and the residue distilled in vacuo after thoroughly washing with water and sodium carbonate solution. The 2-methyl-thiophan-3,4-dicarboxylic-acid-diethyl-ester boils at a pressure of 0.02 mm. at 88 to 90° C. as a colourless oil.

The preparation of 2-(omega-methoxybutyl)-thiophan-3,4-dicarboxylic-acid-diethyl-ester is described in our copending application 585,570. In this synthesis, 80 parts by weight of finely pulverised potassium cyanide are added to a solution of 260 parts by weight of 2-(omega-methoxybutyl)-3-oxo-thiophan-4-carboxylic-acid-ethyl-ester in 540 parts by volume of dibutyl ether and then 106 parts by volume of concentrated hydrochloric acid allowed to drop in during 8 hours while stirring and cooling with ice. The reaction mixture is left to stand overnight at 0° C. The crystallized cyanohydrin with the potassium chloride is separated from the dibutyl-ether solution by suction. The separation of the cyanohydrin from the potassium chloride is effected by dissolving the former in chloroform. The chloroform solution is dried with sodium sulphate and after filtration brought to dryness in vacuo at a bath temperature of 30° C. The 2-(omega-methoxybutyl)-3-hydroxy-3-cyano-thiophan-4-carboxylic-acid-ethyl-ester, obtained in almost theoretical yield, has a melting point of 88° C. The methyl ester melts at 81.5 to 83.5° C.

287 parts by weight of 2-(omega-methoxybutyl)-3-hydroxy-3-cyano-thiophan-4-carboxylic-acid-ethyl-ester are reacted with a mixture of 600 parts by volume of concentrated hydrochloric acid, 300 parts by volume of water and 1100 parts by volume of ethyl alcohol and boiled under reflux for 48 hours. After evaporation in vacuo, the saponified product is converted into the 2-(omega-methoxybutyl)-3-hydroxy-thiophan-3,4-dicarboxylic-acid-diethyl-ester by means of ethyl alcohol and hydrogen-chloride gas. It boils at a pressure of 0.07 mm. at 145-147° C. as a light-yellow, viscous oil. The dimethyl ester boils at a pressure of 0.09 mm. at 146-149° C.

334 parts by weight of 2-(omega-methoxybutyl)-3-hydroxy-thiophan-3,4-dicarboxylic-acid-diethyl-ester are dissolved in 660 parts by volume of chloroform and reacted with 154 parts by weight of absolute pyridine and 231 parts by weight of thionyl chloride while cooling with ice. Reaction and working-up in accordance with the process as applied to the methyl-substituted compound described above yields a yellowish-brown,

viscous oil, viz. 2-(omega-methoxybutyl)-3-chloro-thiophan-3,4-dicarboxylic-acid-diethyl-ester, melting point 138-143° C. at 0.03 mm. The dimethyl ester boils at 134 to 137° C. under a pressure of 0.03 mm.

5 353 parts by weight of 2-(omega-methoxybutyl)-3-chloro-thiophan-3,4-dicarboxylic-acid-diethyl ester are dissolved in 5100 parts by volume of 80 per cent. acetic acid, 230 parts by weight 10 of potassium iodide are added, and, while stirring, 1550 parts by weight of zinc dust are introduced in small portions in the course of 4 hours at a temperature not exceeding 20-25° C. After working-up in accordance with the process as applied to the methyl-substituted compound described above, the 2-(omega-methoxybutyl)-thiophan-3,4-dicarboxylic-acid-diethyl-ester boils as a light-yellowish oil at 148 to 150° C. under a pressure of 0.03 mm. The 2-(omega-methoxybutyl)-thiophan-3,4-dicarboxylic-acid-diethyl-ester boils at 141 to 143° C. under a pressure of 0.03 mm.

20 According to the present invention, 2-(omega-methoxybutyl)-thiophan-3,4-dicarboxylic-acid-ester is reacted with hydrazine-hydrate. The mother-liquor, which remains behind after separation of a crystallising compound, is treated with sodium-nitrite, the acid azide thus resulting is decomposed to yield 3,4-diurethane by heating with 25 alcohol, the solution is evaporated under reduced pressure, and from the benzene solution of the residue a fraction capable of being eluted comparatively easily is separated by chromatography. The more difficultly elutable fraction is converted 30 into the dihydrobromide of 2-(omega-bromo-butyl)-3,4-diamino-thiophan by heating with hydrobromic acid and the resulting salt reacted with phosgene. Potassium-cyanide and a saponifying agent are successively caused to act 35 on the resulting reaction product, whereupon, after acidification, the resulting 2-(omega-carboxy-butyl)-3,4-(imidazolidone-2')-thiophan can be isolated in crystalline form.

40 The isolation of the crystalline final product can, for instance, be effected by esterifying the resulting 2-(omega-carboxy-butyl)-3,4-(imidazolidone-2')-thiophan, crystallising the ester from the eluate after chromatographic purification and, for the purpose of obtaining the crystalline carboxylic acid, a saponifying agent is 45 caused to act thereon.

The compound thus obtained has the following formula:

55 The sterically uniform, racemic compound 60 crystallises in colorless needles melting at 233-235° C.; it is not soluble in ether, difficultly soluble in cold water and more easily soluble in ethyl and methyl alcohol. When biologically tested, the product shows the action of biotin 65 with regard to the growth of *Saccharomyces cerevisiae* and *Streptococcus lactis*.

Example

70 318.5 parts by weight of 2-(omega-methoxybutyl)-thiophan-3,4-dicarboxylic-acid-diethyl-ester are dissolved in 1650 parts by volume of methanol and boiled under reflux with 200 parts by weight of hydrazine-hydrate for 72 hours. On cooling, a dihydrazide of melting point 204-75 205° C. separates. The mother-liquor is evapo-

rated in vacuo and the oily product thus obtained is used for further proceedings.

290 parts by weight of oily 2-(omega-methoxybutyl)-thiophan-3,4-dicarboxylic acid - dihydrazide are dissolved in 835 parts by volume of 3 n-hydrochloric acid, covered with a layer of 8000 parts by volume of ether and treated with a solution of 138 parts by weight of sodium-nitrite in 1000 parts of water added dropwise, while stirring and cooling with ice. The ether-solution containing the azide is evaporated in vacuo at a bath-temperature of 25° C., the residue taken up in 7000 parts by volume of absolute alcohol and transformed into the urethane by heating to 75° C. The alcoholic solution is completely evaporated in vacuo; the residue contains the urethane in the form of a viscous oil. The same is dissolved in 5000 parts by volume of benzene, whereupon the solution is adsorbed onto an aluminum-oxide-column. After washing with benzene, elution is effected with chloroform; the eluate is brought to dryness under reduced pressure.

348 parts by weight of 2-(omega-methoxybutyl)-3,4-diurethano-thiophan are heated to 100-105° C. with 4000 parts by volume of 48 per cent hydrobromic acid until the evolution of carbon-dioxide has come to an end. After evaporation of the hydrobromic acid in vacuo, the dihydrobromide remains behind as a hygroscopic mass.

415 parts by weight of 2-(omega-bromobutyl)-3,4-diamino-thiophan-dihydrobromide are dissolved in 2000 parts by volume of an aqueous n-solution of caustic soda and, while stirring and cooling with ice, treated with 99 parts by weight of phosgene (in form of a 20 per cent solution in toluene) and 2000 parts by volume of an aqueous n-solution of caustic soda, the lye and the phosgene-solution being added simultaneously in such a manner that the pH of the solution is 7 to 8. The reaction product is brought to dryness in vacuo, extracted with alcohol and the alcohol solution evaporated in vacuo. The crude product thus obtained is immediately worked up further.

279 parts by weight of 3,4-(imidazolidone-2')-2-(omega-bromobutyl)-thiophan in 2000 parts by volume of alcohol are boiled under reflux for 24 hours with 65 parts by weight of potassium-cyanide. After evaporation of the alcohol, 112 parts by weight of potassium-hydroxide in 2000 parts of water are added and saponified for 2 hours at 90° C. The alkaline solution is filtered, set acid to Congo with hydrochloric acid and concentrated in vacuo.

The residue is dissolved in methyl alcohol, esterified with diazo-methane and evaporated in vacuo. The remaining oil is dissolved in chloroform, whereupon the solution is adsorbed onto an

aluminum-oxide-column. The chromatogram is first washed with chloroform, whereupon the ester is eluted with acetone. Upon concentration of the acetone-eluate, the dl-3,4-(imidazolidone-2')-2-(omega-carbomethoxy - butyl)-thiophan crystallises in colorless needles which, after recrystallisation from acetic ester or methyl-alcohol-ether mixture, show a melting point of 131-132° C. For saponification purposes, the methyl-ester is heated for a short while with a dilute aqueous solution of caustic soda. After adding hydrochloric acid to the solution until it reacts acid to Congo, the dl-3,4-(imidazolidone-2')-2-(omega-carbohydroxy - butyl)-thiophan crystallises out. After recrystallisation from water, the crystal needles show a melting point of 233-235° C.

Subject matter disclosed herein but not claimed in this application is claimed in applicants' co-pending application Serial No. 744,774, filed April 29, 1947.

We claim:

1. Process for the manufacture of a thiophan derivative, comprising reacting 2-(omega-methoxy-butyl)-thiophan - 3,4 - dicarboxylic - acid-ester with hydrazine-hydrate, treating the mother-liquor remaining after separation of crystalline hydrazide with sodium-nitrite, decomposing the resulting acid azide by heating with alcohol to yield the 3,4-diurethane, evaporating the solution under reduced pressure, dissolving the residue in benzene, passing the solution through a column of aluminum oxide, washing with benzene, eluting with chloroform, evaporating to dryness and converting the residue into the dihydrobromide of 2-(omega-bromobutyl)-3,4-diamino-thiophan by heating with hydrobromic acid, reacting the resulting salt with phosgene, successively causing potassium-cyanide and a saponifying agent to act on the resulting reaction product and isolating the resulting 2-(omega-carboxy-butyl)-3,4-(imidazolidone-2')-thiophan in crystalline form after acidification.
2. Process in accordance with claim 1, comprising esterifying the resulting 2-(omega-carboxy - butyl) - 3,4 - (imidazolidone-2') - thiophan, dissolving the ester in chloroform, passing the solution through a column of aluminum oxide, washing with chloroform, eluting with acetone, crystallising the ester from the eluate and causing a saponifying agent to act thereon for the purpose of obtaining the crystalline carboxylic acid.
